United States Patent Office.

LEOPOLD SALOMONS, OF LONDON, ENGLAND, ASSIGNOR TO J. W. CHISHOLM AND K. CHISHOLM, OF NEW YORK CITY.

Design No. 4,381, dated October 4, 1870.

DESIGN FOR A MEDALLION OR CAMEO.

The Schedule referred to in these Letters Patent and making part of the same.

To all whom it may concern:

Be it known that I, LEOPOLD SALOMONS, of London, England, have invented or produced a new and original Design for a Medallion or Cameo, the said design being an *alto reliefo* of Charles Dickens.

The accompanying photographs of the said design correctly represent the same.

The face is shown nearly in profile, or in the position usually known as "quartering," and upon the side where the hair is parted; the ear, beard, and mustasche being shown, and the collar around the neck, and the upper part of the drapery.

This design may be made in plastic composition, or of any suitable material.

I claim as my invention—

The design of the relief figure of Charles Dickens, shown and described.

Dated the 9th day of August, 1870.

LEOPOLD SALOMONS.
